UNITED STATES PATENT OFFICE.

KENNETH DAVIS, OF ST. BENEDICT, PENNSYLVANIA, ASSIGNOR, BY MESNE ASSIGNMENTS, TO REMBRANDT PEALE, OF ST. BENEDICT, PENNSYLVANIA, W. SANDERS DAVIES, OF NEW YORK, N. Y., AND WILLIAM S. WALLACE, OF PHILADELPHIA, PENNSYLVANIA, TRUSTEES.

ELECTRICAL WINDING MECHANISM.

Application filed August 24, 1920. Serial No. 405,696.

The invention relates to a novel electrically driven hoisting or winding mechanism. The objects and advantages of the invention will be set forth in part hereinafter and in part will be obvious herefrom, or may be learned by practice with the invention, said objects and advantages being realized and attained through and by means of the instrumentalities and combinations pointed out in the appended claims.

The invention consists in the novel parts, constructions, arrangements, combinations and improvements herein shown and described.

The accompanying drawings referred to herein and constituting a part hereof, illustrate one embodiment of the invention, and together with the description, serve to explain the principles of the invention.

Of the drawings:—

Fig. 1 is a central vertical section through a winding or hoisting mechanism constructed in accordance with the invention, and showing certain of the parts in elevation;

Fig. 2 is an end elevation, looking at Fig. 1 from the left, and showing the driving gearing in transverse section on the line 2—2 of Fig. 1;

Fig. 3 is a fragmentary elevation of the central part of Fig. 1, looking thereat from the right, and showing certain parts in section on the line 3—3 of Fig. 1; and

Fig. 4 is a detailed, diagrammatic view of a form of starting or circuit controlling mechanism;

Fig. 5 is a section similar to Fig. 1, but showing a double drum arrangement for simultaneously raising and lowering or winding and unwinding.

In the present preferred and herewith illustrated embodiment of the invention, and referring preliminarily to the general features thereof, an electrically driven winding or hoisting mechanism is provided which is of very compact structure, which has relatively few parts, and which is provided with simple and efficient controls.

In such exemplified embodiment, the greater part of the mechanism is incased inside of the winding drum, that is, the winding drum has disposed therewithin, and preferably

concentrically therewith the electrical driving mechanism. As embodied, this mechanism comprises a shaft concentric with the drum, the drum and shaft both being rotatable in their bearings and being also rotatable relatively to each other. The electrical motor drive is inclosed within the drum as a casing, and is mounted in part upon the casing and in part upon the inclosed concentric shaft, the motor field being fixed to one and the rotor to the other. As embodied, the field is mounted on the interior of the winding drum, and the rotor or armature is mounted on the shaft.

As driving connections between the shaft and drum is mounted power transmitting and speed reducing gearing, and this in the present embodiment is located exteriorly to the drum at one end thereof, and is provided with suitable controls. These controls, as embodied, comprise two brakes, applied to different parts of the gearing to control the drive of the drum by the motor.

Other features of the invention will be primarily set forth in connection with the appended detailed description, and it will be understood that both the preceding and following descriptions are exemplary and explanatory of the invention and not restrictive thereof.

Referring now in detail to the embodiment of the invention illustrated by way of example in the accompanying drawings, a hollow cylindrical winding drum 1, having preferably annular flanges 2 and 3 at either end thereof, is journaled in bearings 4 and 5, which are mounted on pillars 6 and 7, the pillars projecting upwardly from the bed 8 of the machine.

The drum 1 is provided at each end thereof, as a part of its journal mounting, and to provide bearings for the inclosed, concentric shaft, with concentric cylindrical sleeves 10 and 11, these sleeves being surrounded, respectively, with bushings 12 and 13, which bushings are carried in the bearings 4 and 5. Within the sleeves 10 and 11 are bushings 14 and 15, extending into the interior of the drum 1 and provided within the drum with shouldered collars 16 and 17, respectively, which maintain the bushings against longi-

tudinal displacement in a direction externally of the drum.

Journaled in the sleeves 14 and 15 of the drum 1 is a shaft 20, which extends outwardly, to the left in Fig. 1 beyond the bearing 4, to constitute a support and connection for the gearing which constitutes the connections between the motor and drum, and which cooperates with the drum controls, as will be later described.

In the present embodied form, the field magnets are fixed to the interior of the drum 1 and the rotating armature is mounted upon the shaft 20. As shown, two or more field magnets 21 and 22 have their pole pieces fixed to the interior of the drum 1 in suitable manner, as by counter-sunk screw bolts 23 passing through the wall of the drum and into the respective pole pieces. The winding 24 for the field magnets may be of any suitable form for winding or hoisting work, according to the best electrical practice, and they are shown somewhat conventionally in the drawing. The pole pieces may be of any suitable form and number, likewise, in accordance with known practice.

The other electrical connections may be of any desired and efficient form for use in work of the kind intended, and they also are shown herein in partly conventional form. As so shown, a current wire 26 is connected to a screw threaded pin 27, mounted in an insulated bushing 28 in the frame member 7. The pin 27 is integral with, or connected to, a cylindrical socket 29, within which is a pin 30, which pin is impelled by a coiled spring 31 into contact with a ring 32, which ring is fixed upon the detachable head 33 of the drum 1. The head 33 is fastened in position by suitable means, and as shown is provided with an annular flange, fitting within the drum, and is provided also with screw bolts 35 passing through the head and threading into the flange 3 of the drum 1.

The ring 32 is mounted on an insulating support 36 upon the head 33, and is fastened by screws 37 passing through the insulation. The armature 25 is provided with a commutating or distributing ring 40, with which engages a brush 41. Brush 41 is mounted on a spring support 42, carried on a shaft 43, which shaft is insulated in the head 33 of the drum, and is held in place on head 33 by a screw 44. A wire 45 connects the brush 41 with the ring 32.

Cooperating also with the ring 40 is a brush 49, mounted upon a spring 50, which spring is supported from a shaft 51. Shaft 51 is insulated in the head 33 of the drum and held in position on head 33 by a screw 52. A wire 53 goes from the brush 49 to the windings 24 of the field magnets. As stated, heretofore, the electrical connections may be of such form according to established and known practice as will best adapt them for the work to be done.

In Fig. 4 a form of starting switch is shown, designed to be "fool-proof" and as embodied, comprises a switch lever 59 mounted for unidirectional rotation upon, and suitably insulated from, the machine frame. As embodied, the lever 59 has fixed thereto, to rotate therewith, a spring-pressed pawl 60, which is in engagement with the teeth of a ratchet wheel 61, fixed upon the machine frame. The arm or lever 59 is adapted to make successive electrical contact with two contact pieces 62 and 63, contacting first with the strip 62 and then with the strip 63, but passing into contact with the latter before passing out of contact with the former.

Switch lever 59 is in circuit with the supply wire 26 for the motor. The contact strip 62 is in circuit with a wire 64, coming from the electrical mains, a resistance 65 being interposed in the circuit. The contact strip 63 connects directly to the supply wire 64 without the intervening resistance.

To start the machine, as the switch lever 59 will move only in the direction of the arrow, it closes the circuit first through the contact strip 62 and the resistance 65 and then through the contact strip 63, then cutting out the resistance 65, and by this means too much and too sudden current inrush, arcing, and other evils are avoided.

Referring now to the gearing connections and the controls therefor, an eccentric 70 is fixed to the shaft 20 to rotate therewith by a key 71. Mounted on the exterior of the eccentric 70 is a cylindrical bushing 72, and loosely mounted on the bushing 72 are two geared pinions 73 and 74. Pinions 73 and 74 have a different number of gear teeth and preferably differ in number by only one or two teeth. The geared pinions 74 and 73 are connected together in a suitable manner, as by rivets or pins 75 passing therethrough, so that they will rotate together.

Meshing with the geared pinion 73 is an internal gear 77, which is inclosed within a brake drum 79, and is fixed by means of a key 78 to the brake drum. Brake drum 79 is journaled loosely on a sleeve 80, which loosely encircles the armature shaft 20. A nut 81 serves to hold the brake drum in position upon the shaft. The geared pinion 74 is in mesh with an internal gear ring 84, which is inclosed within a brake drum 85 and is fixed to the brake drum by a key 86. Brake drum 85 is fixed to or integral with the sleeve 10 of the winding drum 1. The two brake drums are not connected, except through the gearing, and are capable of relative movement under certain conditions of the connections. Encircling the brake drum 79 is a brake band 87, which is provided with an actuating lever 88, pivoted at 89, and which may be of any suitable and adequate form. Encircling brake drum 85 is a brake band 90, which may be of similar form to, and may

be provided with similar actuating means as, 10
brake band 79.

The manner of operation of the gearing is substantially as follows:—

5 As the armature shaft 20 rotates, due to the eccentric mounting of geared pinion 73, the pinion passes around the internal gear ring 77 sequentially about its circumference, the gear teeth of the pinion likewise meshing sequentially with those of the gear ring. The pinion has backward rotation relatively to the gear ring for each revolution of the shaft 20 equal to the difference in the number of teeth on the pinion 73 and on the gear ring 15 74. This is usually very small and gives a relatively large reduction between the rotations of shaft 20 and those of the geared pinion 73.

The pinion 74 rotates with the pinion 73, 20 and is adapted to roll along the inner circumference of gear ring 84 in the same manner as pinion 73 rolls on gear ring 77. Pinion 74 is adapted to impart to the drum 1 rotation in an opposite direction, and for a distance, 25 during each rotation of pinion 74, equal to the difference in the number of teeth on the geared pinion 74 and on the internal gear ring 84.

When the brake band 87 is tightened, and 30 brake band 90 is loose, gear ring 77 is held against rotation, but gear ring 84 is free to rotate. As armature shaft 20 rotates, pinion 73 rolls on internal gear ring 77 and the pinion has a backward rotation about its own 35 axis for the fraction of a rotation equal to the difference between the number of teeth on gear ring 77 and pinion 73, and as gear ring 84 is free to rotate, it will rotate forwardly very slowly, proportionately to the difference in the number of teeth between pinion 74 and gear ring 84. Thus drum 1 rotating with gear ring 84 will make a small fraction of a rotation for each rotation of armature shaft 20. When brake band 87 is 40 loose and brake band 90 is tightened, the drum 1 is held at rest while armature shaft 20 may be permitted to rotate idly, the differential reverse rotation of the pinions due to pinion 74 being in mesh with gear ring 84 (which is held stationary by brake band 90) causing gear ring 77 and drum 79 to turn idly on sleeve 80. The two brake levers thus provide a complete control for the drum 1 independently of the running of the motor, the switch 55 59 providing the motor control.

In Fig. 5 a double drum construction embodying the invention is shown. The reference numerals used in the preceding figures are applied to the same or corresponding parts 60 as they appear in this figure.

As embodied, the additional drum 95 is integral with or fixed to the housing 79, which in the construction of Figs. 1 and 2 serves also as a brake drum for brake 87 as well as 65 for a housing and support for the fixed inter-

nally geared ring 77. In this construction the brake is applied elsewhere as will be later described.

Also, in Fig. 5 the other brake drum 85, 70 while still used as a brake drum and as a support within which the other internally geared ring 84 is fixed, is also extended in a general cylindrical form so as to constitute a housing 96 about the entire gear mechanism. The end of the housing 96 is closed by a flat circular plate 97, fixed to the periphery of the housing by suitable means, such as bolts 98. The interior of the housing may be supplied with lubricant and the entire gear mechanism thus may be run in the lubricant. 80

The plate 97 is centrally apertured and provided with a hub 99, within which is a sleeve 100. Journaled in sleeve 100 is a shaft 101, fixed to or integral with the gear housing 79 and with the drum 95. The plate 97 85 is also preferably provided with a bearing ring 102 running against the flat face of the housing 79. This will usually provide a sufficiently strong and rigid connection, but a journal bearing may be provided, if desired, 90 for the shaft 101 or hub 99.

Drum 95 at its opposite end is provided with a suitable bearing, and is shown with a hollow hub or shaft 105, encircled by a sleeve 106, which is journaled in a bearing 107 on the frame pillar 108. The brake band 87^a 95 acts upon the part 109 of the winding drum, having its connection to the gearing through shaft 101.

In Fig. 5 the mounting for the pinions 73 100 and 74 is of somewhat different form than in Figs. 1 and 2. In Fig. 5 armature shaft 20 has fixed to the end thereof a double arm 112, the arm being fixed to the shaft intermediate 105 of its ends by a pin 113. On one end of arm 112 is a shaft 114 on which the pinions 73 and 74 are rotatably mounted, while on the other end of arm 112 is a counterweight 115 designed to balance the pinions about the shaft 20. 110

The manner of operation of the mechanism shown in Fig. 5 is substantially as follows:—

When both brake bands 87^a and 90 are set, both winding drums 1 and 95 are held against motion, and therewith, respectively, the gear rings 84 and 77. 115

If brake 90 is released and brake 87^a remains set, drum 95 and therewith gear ring 77 will be held stationary. This will cause pinion 73 to sweep around on gear ring 77, the gear teeth on the two meshing sequentially, but the pinion will have a partial relative rotation with respect to gear ring 77 for each revolution of shaft 20 proportional to the extra member of gear teeth on the ring 77. Pinion 74 is fixed to pinion 73 to rotate therewith. Pinion 74 sweeps around on gear ring 84 (which is free to rotate by reason of brake 90 being released), and imparts a backward rotation to gear ring 84 and therewith to 120 125 130

drum 1 proportional to the difference in the number of gear teeth on pinion 74 and gear ring 84. This gives a very slow rotation of drum 1 relatively to its driving shaft 20.

5. If brake 87^a is released and brake 90 remains set, the action will be the same except in this case gear ring 84 is held stationary and gear ring 77 and therewith drum 95 is rotated by reason of pinion 73 turning with pinion 10 74. Thus drum 95 will be rotated very slowly compared with the rotation of its driving shaft 20.

The invention in its broader aspects is not limited to the specific mechanism shown and 15 described but departures may be made therefrom within the scope of the accompanying claims without departing from the principles of the invention and without sacrificing its chief advantages.

20. What I claim is:—

1. An electrically propelled winding mechanism comprising a rotatable winding drum, a shaft concentric therewith, an electrical motor for the shaft within the drum including a field and rotor, a second winding drum, and 25 connections whereby the motor may selectively drive either drum at a reduced speed with respect to the shaft.

2. An electrically propelled winding mechanism comprising a rotatable winding drum, a shaft concentric therewith, an electrical motor for the shaft within the drum including a field and rotor, a second winding drum, and a single gear mechanism connected to the 30 shaft and adapted to selectively drive either drum at reduced speed with respect to the shaft.

3. An electrically propelled winding mechanism comprising a rotatable winding drum, 40 a shaft concentric therewith, an electrical motor for the shaft within the drum including a field and rotor, a second winding drum, connections whereby the motor may selectively drive either drum at a reduced speed with respect to the shaft, and brake control mechanism for said connections.

4. An electrically propelled winding mechanism comprising a rotatable winding drum, a shaft concentric therewith, an electrical motor for the shaft within the drum including a field and rotor, a second winding drum, a single gear mechanism connected to the shaft and adapted to selectively drive either drum at reduced speed with respect to the shaft, and 50 brake control mechanism for said gearing.

5. An electrically propelled winding mechanism comprising a rotatable winding drum, a shaft concentric therewith, an electrical motor for the shaft within the drum including a fluid and rotor, a second winding drum, connections whereby the motor may selectively drive either drum at a reduced speed with respect to the shaft, a brake acting on one of 60 said drums and a brake acting on the other

drum to control the operation of said connections on the drums.

6. An electrically propelled winding mechanism comprising a rotatable winding drum, a shaft concentric therewith, an electrical motor for the shaft within the drum including a field and rotor, a second winding drum, a single gear mechanism connected to the shaft and adapted to selectively drive either drum at reduced speed with respect to the shaft, a 70 brake acting on one of said drums and a brake acting on the other drum to control the operation of said gearing on the drums.

7. An electrically propelled winding mechanism comprising a winding drum, a second winding drum, a driving shaft common to both drums, an internally geared ring rotating with one drum, an internally geared ring rotating with the other drum, a pair of pinions geared with the gear rings, respectively, and mounted eccentrically on said driving 80 shaft, and a motor for the shaft mounted within one of the drums.

8. An electrically propelled winding mechanism comprising a winding drum, a second winding drum, a driving shaft common to both drums, an internally geared ring rotating with one drum, an internally geared ring 90 rotating with the other drum, a pair of pinions geared with the gear rings, respectively, and mounted eccentrically on said driving shaft, and a motor for the shaft mounted within one of the drums, including a rotor 95 on the shaft.

9. An electrically propelled winding mechanism comprising a winding drum, a second winding drum, a driving shaft common to both drums, an internally geared ring rotating with one drum, an internally geared ring 100 rotating with the other drum, a pair of pinions meshing with the gear rings, respectively, and mounted eccentrically on said driving shaft, a brake for each drum, and a motor for the shaft mounted within one of the drums.

10. An electrically propelled winding mechanism comprising a winding drum, a second winding drum, a driving shaft common to both drums, an internally geared ring rotating with one drum, an internally geared ring 110 rotating with the other drum, a pair of pinions meshing with the gear rings, respectively, and mounted eccentrically on said driving shaft, a brake for each drum, and a motor for the shaft mounted within one of the drums including a rotor on the shaft.

11. An electrically propelled winding mechanism comprising a rotatable drum, a shaft journaled therethrough and rotatable relatively thereto, an electrical motor on said shaft within said drum, an eccentric fixed on said shaft outside said drum, two pinions loosely mounted on said eccentric and fixedly interconnected, two internal gears, one of 120

which is journaled on said shaft, said gears enclosing said eccentric and pinions, one of said internal gears being rigid with said drum and each of said internal gears meshing with a pinion, and a brake for each internal gear.

12. An electrically propelled winding mechanism comprising a winding drum provided with an axial lateral sleeve having an internal gear connected thereto, a motor shaft journaled in said sleeve and adapted to rotate relatively to said drum, a motor on

said shaft enclosed by said drum, a second internal gear disposed beside said first-mentioned gear, concentrically to the axis of said shaft, an eccentric fixed to said shaft within said gears, a pair of interconnected pinions freely journaled on said eccentric and adapted to be in mesh with said internal gears on rotation of said eccentric, and means to brake said internal gears independently. 15

In testimony whereof, I have signed my name to this specification.

KENNETH DAVIS.
